DESIGN FOR PADLOCKS.

Specification forming part of Design No. **11,305**, dated July 29, 1879; application filed May 10, 1879.
[Term of patent 14 years.]

UNITED STATES PATENT OFFICE.

RODOLPHE CHRISTESEN, OF HARTFORD, ASSIGNOR TO THE RUSSELL & ERWIN MANUFACTURING COMPANY, OF NEW BRITAIN, CONNECTICUT.

DESIGN FOR PADLOCKS.

Specification forming part of Design No. **11,305**, dated July 29, 1879; application filed May 10, 1879.
[Term of patent 14 years.]

To all whom it may concern:

Be it known that I, RODOLPHE CHRISTESEN, of the city and county of Hartford, and State of Connecticut, have invented a new and useful Design for Padlocks; and I do hereby declare that the following specification, taken in connection with the accompanying photographic illustration, forming a part of the same, is a full, clear, and exact description thereof.

My design consists in a segmental case cut away at its periphery in radial lines, which are joined at their bases by an outwardly-curved line, and ornamented on the side of the case with a continuous border and a central column with a heavy-flowered cap flanked by sun-rays and fringed lines, which extend from the column on each side to the radial lines.

As shown in the illustration, the case A is segmental in outline, and is broken away at its periphery in radial lines *a*, the bases of which are joined by the outwardly-curved line *a'*. The hasp B, being also segmental and

having an outline corresponding with that of the case, crosses the break therein, and completes the circle, inclosing a space corresponding in its outline to the segment of a ring. The side of the case has a continuous border. The key-hole is located in a central column surmounted by a flowered cap, and flanked by sun-rays and fringed lines, which extend from the sides of said column to the adjacent radial lines *a*.

What I claim, and desire to secure by Letters Patent, is—

A design for a padlock-case segmental in its outline, cut away at its periphery in radial lines, which are joined at their bases by an outwardly-curved line surrounded by a border, and bearing on its side a central column surmounted by a flowered cap and flanked by sun-rays and fringed lines, substantially as shown and described.

RODOLPHE CHRISTESEN.
